FIG. 5

INVENTOR,

Charles E. Christenson,
BY
Frazer and Richards,
ATTORNEYS.

UNITED STATES PATENT OFFICE.

CHARLES E. CHRISTENSON, OF SOUTH ORANGE, NEW JERSEY.

ANTISQUEAK CUSHION FOR AUTOMOTIVE BRAKES.

Application filed February 11, 1925. Serial No. 8,395.

This invention relates, generally, to improvements in brakes for automotive vehicles and the like; and the invention has reference, more particularly, to a means in combination with the brake-bands and their linings adapted to provide against squeaking, squealing and chattering when the brake-bands are tightened on the brake-drums.

10 The invention has for its principal object to provide a resilient cushion intermediate the ends of the brake-lining and the brake-band, whereby the shock and stress of initially applied pressure in operating the 15 brakes is absorbed and compensated, so that operative pressure of the brake-band is more evenly distributed around the brake-drum, and tendencies of the brake-lining to chatter and squeak, by reason of unequal distribution of friction, is eliminated.

20 The invention has for a further object to provide a novel means for applying the resilient cushions in proper assembled relation to brake-bands and their linings, both in 25 connection with new and old brake assemblies.

Other objects of this invention, not at this time more particularly enumerated, will be clearly understood from the following detailed description of the same.

The invention is clearly illustrated in the accompanying drawings, in which:—

Fig. 1 is a plan view of a resilient cushion member, made according to and embodying the principles of this invention, the same being detached from operative relation to a brake-band and its lining; Fig. 2 is a similar plan view with the novel applying tool or clip attached thereto, and by aid of which the cushion may be operatively assembled with a brake-band and its lining; Fig. 3 is a longitudinal section taken on line 3—3 in Fig. 2; Fig. 4 is a transverse section taken on line 4—4 in Fig. 2; Fig. 5 is a side elevation of a brake-drum and brake-band with its lining, the same illustrating the novel resilient cushion members operatively assembled in connection with said brake-band and lining; and Fig. 6 is a fragmentary transverse section, taken on line 6—6 in Fig. 5.

Similar characters of reference are employed in all of the hereinabove described views, to indicate corresponding parts.

55 Referring now to said drawings, the ref-

erence character 1 indicates the novel resilient cushion member. The said cushion member 1 consists of a preferably rectangular body, which may be of a thickness preferably not exceeding one-eighth of an inch, 60 and of a length somewhat exceeding the width of the brake-band and lining with which the same is to be assembled. The said cushion 1 is preferably made of rubber, but the same may also be made of any other 65 material possessing resilient or elastic qualities.

In Figs. 5 and 6 I have illustrated a brake-drum 8, and a brake-band 6 with its lining 7 to cooperate with said brake-drum, 70 and in connection therewith I have shown my novel anti-squeak and anti-chatter cushions 1 assembled in desired operative relation to the brake-band and its lining. When thus assembled, a cushion member 1 is introduced between the brake-band 6 and lining 7 adjacent to each end of said brake-band. Ordinarily, when the brake-band 6 is actuated to contract the same around the circumference of the brake-drum 8, and thus cause the lining 7 to frictionally bind upon or grip the brake-drum surface, the outer end portions of the brake-lining 7 will be immediately thrust or jammed against the brake-drum surface, and as a result, before 80 the frictional grip of the lining is equally distributed along the brake-drum surface, there is a tendency of the brake-band lining to squeak, squeal or chatter. When, however, my novel cushion members are inserted 85 between the end portions of the brake-band and its lining, and the brake band is actuated or contracted, the first thrust of the end-portions of the lining against the brake-drum surface is partially absorbed by the 90 cushions 1, so that said end-portions will yield radially outward relative to the brake-drum, until the contraction of the brake-band draws the lining firmly and evenly down upon the brake-drum surface, thus 95 uniformly distributing the frictional pressure, and therefore eliminating all tendency to speak, squeal or chatter.

In order to make easy and convenient the process of assembling the cushions 1 in operative relation to the brake-band 6 and its lining 7, and especially when applying said cushions to old equipment, I provide adjacent to one end of each cushion 1 a transverse row of perforations or eyes 3, and I 110

also provide a novel attaching tool or clip 2 which is designed to cooperate with the perforate end of the cushion 1, so as to be coupled therewith. Said attaching tool or clip 2 comprises a main body, preferably made of sheet metal, which is doubled upon itself as shown more particularly in Fig. 3. One free transverse end of said clip body 2 is provided with a plurality of upturned teeth 4, corresponding in number and spacing to the number and spacing of the perforations or eyes 3 provided in the end of the cushion 1. The other free transverse end of said clip body 2 is disposed to form a cover portion 5 adapted to engage and close over the free ends of said teeth 4. It is preferable to taper the width of said clip body 2 from its toothed end toward its doubled end, as shown in Fig. 2.

10 The said attaching tool or clip 2 is operatively coupled with a cushion member 1 by spreading apart the free end portions of the former to receive the perforate end of the latter, so that the teeth 4 may be entered through the perforations or eyes 3, as shown in Figs. 2, 3 and 4. When the attaching tool or clip 2 is thus coupled with a cushion member 1, the doubled or outer end of the tool or clip is inserted, at the desired location, between the brake-band 6 and its lining 7. This operation may be aided by first inserting a screw driver or other sharp tool between the brake-band and its lining, to thus produce an initial separating opening 35 into which the end of the tool or clip may be inserted. The tool or clip having been inserted between the brake-band and its lining, the same is thrust laterally from one side of the brake-band to the other, until its 40 free end projects beyond the opposite side from that at which it was entered, whereupon the operator grasps the outwardly projecting end of the tool or clip and pulls the same on through. The cushion member 1 thereupon follows or is pulled after the tool until it is properly seated intermediate the brake-band and its lining. Since the cover portion 5 closes over or covers the teeth 4, the latter can not catch or otherwise obstruct 45 the movement or passage of the tool or clip between the brake-band and its lining. As before stated the cushion member 1 is made somewhat longer than the width of the brake-band and its lining, and consequently 50 its perforate end, when the cushion is properly positioned, will project outwardly beyond the side of the brake-band and its lining, and, therefore, the tool or clip 2 may be readily detached from the cushion, by 55 separating the free end portions and then

60 withdrawing the teeth 4 from the perforations or eyes 3 of the cushion.

Having thus described my invention, I claim:

1. A resilient cushion for the purposes described having initially attached thereto a removable metallic clip, said clip being disposed in endwise extension from one end of said cushion.

2. A cushion for the purposes described, said cushion comprising a relatively thin resilient body of rectangular shape, said body having a transverse row of perforations adjacent to one end thereof to receive the attachment therewith of a metallic clip for endwise extension therefrom.

3. A cushion for the purposes described, said cushion comprising a relatively thin resilient body of rectangular shape, said body having a transverse row of perforations adjacent to one end thereof, and a detachable metallic clip, said clip comprising a clip body doubled upon itself, one free transverse end of said clip body having a plurality of upstanding teeth to pass through said perforations of said cushion, and the other free transverse end of said clip body providing a cover portion to close over the free extremities of said teeth.

4. The combination with a brake-band and its lining of a resilient cushion member positioned between the brake-band and its lining adjacent to a movable end of said brake-band, said cushion member having initially attached to one end thereof a removable metallic clip for threading and drawing said cushion member into place intermediate said brake-band and its lining.

5. The combination with a brake-band and its lining of a resilient cushion member positioned between the brake-band and its lining adjacent to a movable end of said brake-band, said cushion member having a transverse row of perforations adjacent to one end thereof, and a detachable metallic clip for threading and drawing said cushion member into place intermediate said brake-band and its lining, said clip comprising a body doubled upon itself, one free end of said body having a plurality of upstanding teeth to pass through said perforations of said cushion member, and the other free transverse end of said body providing a cover portion to close over the free extremities of said teeth.

In testimony that I claim the invention set forth above I have hereunto set my hand this third day of January, 1925.

CHARLES E. CHRISTENSON.
